[57] CLAIM

The ornamental design for an outdoorsman's knife, as shown and described.

DESCRIPTION

FIG. 1 is a front elevational view of the outdoorsman's knife showing my new design;

FIG. 2 is a side elevational view thereof;

FIG. 3 is a rear elevational view thereof;

FIG. 4 is a front elevational view thereof with the knife configured to expose a file component;

FIG. 5 is a side elevational view of FIG. 4;

FIG. 6 is a bottom plan view of FIG. 4; and

FIG. 7 is a side elevational view of the knife with blade and file components concealed within a holder.
